UNITED STATES PATENT OFFICE.

WILLIAM J. WATTERS, OF CHICAGO, ILLINOIS, ASSIGNOR TO OFFICE SUPPLY COMPANY, OF CHICAGO, ILLINOIS, A CORPORATION OF ILLINOIS.

BINDER-FRAME.

No. 823,653.

Specification of Letters Patent.

Patented June 19, 1906.

Application filed July 28, 1905. Serial No. 271,586.

To all whom it may concern:

Be it known that I, WILLIAM J. WATTERS, a citizen of the United States, residing at Chicago, in the county of Cook and State of Illinois, have invented new and useful Improvements in Binder-Frames, of which the following is a specification.

This invention relates to loose-leaf binder-frames; and it consists of certain novel and useful improvements on the binder-frame covered by Letters Patent No. 785,924, granted to me on March 28, 1905.

The object of the invention is to simplify, strengthen, and otherwise improve the construction of the frame and also to arrange the working parts wholly within the relatively movable members, so that they will not be disclosed at the back of the frame when the frame is extended to its greatest width.

20 In the accompanying drawings I have illustrated one embodiment of the invention, and, referring thereto, Figure 1 is a plan view of the frame extended to its greatest width, the covers and hinges therefor being omitted. Fig. 2 is a sectional view on the line 2 2 of Fig. 1. Fig. 3 is an end view.

In the drawings, 10 is a back member, and 11 represents two relatively movable members to which the covers are attached by 30 suitable hinges in the usual manner. The ends 13 of the movable members are arranged to work within and close to the ends 14 of the back member, and these ends thus act as guides for the movable members and assist in 35 maintaining the members in proper relative position.

A screw-rod 15 is mounted in brackets 16 within one of the movable members, and a guide-rod 17 is secured in brackets 18 within 40 the other movable member. Two or more parallel cross-pieces 19 are pivotally mounted on studs 20, located rigidly and centrally on the back member and projecting up between the adjacent edges of the movable 45 members. These cross-pieces are pivotally connected at their ends to travelers 21 on the guide-rod and screw-threaded travelers 21' on the screw-rod. The cross-pieces are of equal length, and the movable members are 50 connected together thereby and to the back member, so that the movable members may be moved relatively to the back member and uniformly with each other. This adjustment

is accomplished by means of the screw-rod, which is operated by a key. (Not shown.) 55 One end 15' of the screw-rod is shaped to receive the operating-key, and the adjacent end of the movable member is provided with an opening 22, and the adjacent end of the back member is provided with a slot 22', registering with the opening 22 to permit the key to be inserted therethrough to engage the screw-rod at any time. I prefer to employ guides 23, which are fastened to the back member at each end of the frame and 60 project across the movable members to assist in holding the members in proper relative position. Telescopic posts 24 are provided to receive the leaves in the usual manner.

It will be readily understood that by turning the screw-rod the travelers thereon will be moved lengthwise of the rod, and thereby swing the cross-pieces on their pivots and move the movable members uniformly to expand or contract the frame according to the 70 direction in which the screw may be operated. The movement of the movable members is uniform, and they will therefore always have the same relation to the back member. As the cross-pieces are connected 75 at their ends on one movable member to the screw-rod and on the other movable member to the guide-rod and at their middle to the back member, it is apparent that the relative position of the several members will be 80 constantly maintained.

The means for operating the movable members is all contained within said members, and hence the frame can be expanded to its greatest width without disclosing the parts of 90 this operating means at the back of the frame.

The construction and arrangement of the parts is such that the friction of the moving parts is reduced to a minimum, and this enables the frame to be operated easily. The 95 construction also provides a strong and durable frame which will not become loose and get out of order in usage.

What I claim, and desire to secure by Letters Patent, is—

1. A binder-frame comprising a back member and two relatively movable members, a screw-rod mounted on one of said movable members, a guide-rod on the other movable member, travelers on said rods, and parallel 105 cross-pieces pivotally mounted on the back

member near the ends of the frame and pivotally connected at their ends to said travelers.

2. A binder-frame comprising a back member and two relatively movable members, a screw-rod mounted within one of said members, a guide-rod mounted within the other movable member, a pair of parallel cross-pieces pivotally mounted on the back member near the ends of the frame, a pair of trav-

elers on the guide-rod pivotally connected to the ends of the cross-pieces, and a pair of screw-threaded travelers on the screw-rod pivotally connected to the other ends of the cross-pieces.

WILLIAM J. WATTERS.
